UNITED STATES PATENT OFFICE.

PIETRO SIRENA CORLEO, OF PALERMO, ITALY.

ADJUSTABLE OBSTETRIC FORCEPS.

Application filed December 10, 1926, Serial No. 153,890, and in Italy October 27, 1926.

The subject of the present invention is an improved adjustable obstetric forceps with alternately arranged yielding blades, which is illustrated by way of example in the accompanying drawing, in which:

Figure 1 shows the forceps in the closed position, and

Figure 2 shows the same in the open position, with outspread handles and blades, each of which comprises a divided elastically yielding blade (as in the case in which the instrument is applied in a vertex presentation, with occipito-frontal grip).

The forceps forming the subject of the present invention obviates the known disadvantages attaching to the various types of forceps at present in use, such disadvantages being due to compressive action.

Said action is minimized by means of a suitable shaping of the blades, the shanks of which are made parallel to each other only in one part, according to the English method of articulation (Figure 2), differing from other types of forceps heretofore described, 25 but hinged according to the German method.

As can be seen from Figure 2, the left rear blade member g^2 and the front right blade member g^3 are provided with a longitudinal recess f^3 , which serves as a lodgment for the 30 respective left front blade member g^1 and right rear blade member g^4 .

This arrangement facilitates the sliding of the locking collars f^1 and f^2 which engage respectively with the blade members g^1 , g^2 , 35 and g^3 , g^4 , and the locking of the blade members g^1 , g^4 as in the known forceps. The collars f^1 and f^2 are slid over the shanks of the blades with the greatest ease inasmuch as the blade members are in the same plane.

Figure 1 indicates, by the dotted lines, the positions f^1 and f^2 assumed by the locking collars f^1 and f^2 when moved away from the pin s in order to lock the blade members g^1 and g^4 , whilst in Figure 2 the said locking 45 means are situated in the vicinity of the pivotal point in order to leave the divided blades free to yield.

In Figure 2 the blade-members g^1 and g^2 are in the position corresponding to the act of 50 pressing on the head t and have yielded to an extent corresponding to the oblique left diameter.

In the action of compression the forceps adapts itself to the presented part, the head 55 t becomes fixed so as to prevent any increase of the antero-posterior diameter, and thus

in turn facilitates a corresponding increase d of the right oblique diameter, which increase is more favorable for overcoming the obstacle of the brim of the pelvis, through coinciding with the right oblique diameter of the pelvis.

During the operation of extraction and only in the moment when the presented part is to pass from the brim to the wide portion 60 of the cavity of the pelvis, the operator may, by drawing down the collars f^1 and f^2 release the yielding blade members g^1 and g^4 , so as to pass by the obstacle. Afterwards, by pushing the collars up again, the operation may 70 be completed as with solid forceps.

The instrument according to the present design, possesses the characteristic of being provided with divided blades with the corresponding sliding collars on the shanks, these 75 latter have the same character as those of ordinary forceps.

The forceps now described exerts a minimum of compression on the part presented, thereby reducing the mortality among the 80 newly born. The use of this forceps enables intervention to take place in cases of contracted pelvis of a moderate degree, with a notable reduction in the number of more serious and complicated operative processes. 85

Clinical tests have demonstrated that the fenestrated blade members of the forceps may be divided alternately without lowering the resistance of the instrument to the action of gripping and traction, on the contrary it is 90 of advantage in the rotary action that the alternate discontinuity of the blades transforms the forceps from rigid to flexible grip, with the result that the compressive action of the instrument is considerably lessened, the 95 instrument being no longer subjected to the classic leverage action produced by the compression of the handles; and finally that said reduction in the compressive action, attains the maximum with the blades yielding (5 100 kg.), is also considerable when the blades are locked (7 kg.), and therefore the application of the said instrument, with the locking collars raised, as an ordinary forceps signifies an important advantage over the compressive action of the instruments hitherto in use, which is not less than 18 kg.

I claim:

- An improved obstetric forceps comprising pivotally connected blades, each blade being divided so as to provide a yielding portion and a relatively unyielding portion, a 110

recess in the relatively unyielding portion of each blade, and movable locking collars adapted to lock each yielding portion to its respective unyielding portion.

5. 2. An improved obstetric forceps comprising pivotally connected blades, divided so as to present a yielding portion and a relatively unyielding portion, part of the shanks of the unyielding portions of the blades being par-

10 allele, a recess provided in each said parallel part of the shank, and movable locking collars adapted to lock each yielding portion to its respective unyielding portion in the recess of said unyielding portion.

15 3. An improved obstetric forceps comprising pivoted handles having fenestrae, said fenestrae having divided shanks at the bottom thereof, the front shank of one fenestra and the rear shank of the other being made integral with said pivoted handles, while the remaining shanks are left unattached for the purpose of yielding in case of excessive pressure.

4. An improved obstetric forceps comprising pivoted handles having fenestræ, mounted thereon, said fenestræ having divided shanks at the bottom thereof, the front shank of one fenestra and the rear shank of the other being made integral with said pivoted handles and having movable locking collars slidable thereon engaging said divided shanks. 25 30

5. An improved obstetric forceps comprising pivoted handles having fenestræ mounted thereon, said fenestræ having divided shanks at the bottom thereof, the front shank of one fenestra and the rear shank of the other being made integral with said pivoted handles and having movable locking collars slidable thereon engaging said divided shanks, and recesses provided in said shanks integral with said pivoted handles, the two divided shanks being adapted to be secured in said recesses by the said movable locking collars. 35 40

PIETRO SIRENA CORLEO.
